ANCESTRAL EDUCATIONAL GAMEBOARD

Ernest A. Montemayor, Arlington, Va.
(4600 45th St. NW., Washington, D.C. 20016)

Filed Nov. 8, 1974, Ser. No. 522,062

Term of patent 14 years

Int. Cl. D21—01

U.S. Cl. D34—5 SS

FIG. 1.

FIG. 2.

FIG. 3.

FIG. 4.

FIG. 5.

FIG. 1 is a top plan view of an ancestral educational gameboard showing my new design;

FIG. 2 is an enlarged fragmentary view showing a major portion of the upper left-hand quadrant of the board, of FIG. 1;

FIG. 3 is an enlarged fragmentary view showing a major portion of the lower left-hand quadrant of the board, of FIG. 1;

FIG. 4 is an enlarged fragmentary view showing a major portion of the upper right-hand quadrant of the board, of FIG. 1; and

FIG. 5 is an enlarged fragmentary view showing a major portion of the lower right-hand quadrant of the board, of FIG. 1.

The board is of conventional thickness.

I claim:

The ornamental design for an ancestral educational gameboard, as shown and described.
